[57] CLAIM

The ornamental design for a mini caddy, as shown and described.

DESCRIPTION

FIG. 1 is a top, rear, and right side perspective view of a mini caddy showing our new design;

FIG. 2 is a top plan view thereof;

FIG. 3 is a rear elevational view thereof;

FIG. 4 is a right side elevational view thereof; the left side being a mirror image of that shown;

FIG. 5 is a bottom plan view thereof; and,

FIG. 6 is a front elevational view thereof.

FIG.1.

FIG. 2.

FIG. 3.

FIG. 4.

FIG.5.

FIG.6.
